United States Patent

Des. 237,715
Patented Nov. 18, 1975

237,715

COMPUTER SYSTEM

Dennis P. Butterbaugh and Arthur C. Hanft, Rochester,
Minn., assignors to International Business Machines
Corporation, Armonk, N.Y.

Filed Jan. 21, 1974, Ser. No. 435,141

Term of patent 14 years

Int. Cl. D14—02

U.S. Cl. D26—5 C

FIG. 2

FIG. 3

FIG. 4

FIG. 5

FIG. 6

FIG. 1 is a perspective view of a computer system showing our new design;

FIG. 2 is a front elevational view thereof;

FIG. 3 is a rear elevational view thereof;

FIG. 4 is a top plan view thereof;

FIG. 5 is a right side elevational view thereof; and

FIG. 6 is a left side elevational view thereof.

We claim:

The ornamental design for a computer system, as shown and described.
